(57) CLAIM

The ornamental design for a combined play mat with storage bag, as shown and described.

DESCRIPTION

FIG. 1 is a front and bottom perspective view of a first embodiment of a combined play mat with storage bag, showing our new design;

FIG. 2 is a rear and bottom perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof;

FIG. 9 is another perspective view thereof, shown in an alternative position;

FIG. 10 is an enlarged perspective view of detail “10” identified in FIG. 1;

FIG. 11 is a front and bottom perspective view of a second embodiment of the combined play mat with storage bag;

FIG. 12 is a rear and top perspective view thereof;

FIG. 13 is a front view thereof;

FIG. 14 is a rear view thereof;

FIG. 15 is a left side view thereof;

FIG. 16 is a right side view thereof;

FIG. 17 is a top view thereof;

FIG. 18 is a bottom view thereof; and,

FIG. 19 is an enlarged perspective view of detail “19” identified in FIG. 11.

The dashed lines in the figures illustrate portions of the combined play mat with storage bag that form no part of the claimed design. The dash dot dash lines in FIGS. 1, 10, 11 and 19 are for the purpose of illustrating the enlarged views indicators and form no part of the claimed design.
